Fig. 6

Fig. 1 is a plan view of woven slat fabric showing on full scale one embodiment of my design, parts being broken away for convenience of illustration, and the interlacing cords shown in phantom,

Fig. 2 is a horizontal sectional view taken along the lines 2—2 of Fig. 1,

Fig. 3 is a view similar to Fig. 1 wherein the perforations are oval-like in shape,

Fig. 4 is a view similar to Fig. 3 wherein the perforations are diamond-like in shape,

Fig. 5 is a view similar to Fig. 1 wherein the wide slats are perforated, and

Fig. 6 is a view similar to Fig. 1 wherein the perforated slats vary as to the number of perforations in an alternating manner.

My design comprises a series of wide and narrow slats interlaced as by yarn or cord with alternate slats being perforated at intervals along their length.

I claim:

The ornamental design for a woven slat fabric, as shown and described.
